BREAD SLICING MACHINE

Harry J. Criner, Davenport, Iowa, assignor of one-half to A. G. Bush, Davenport, Iowa

Application November 6, 1937, Serial No. 173,134

20 Claims. (Cl. 146—88)

My invention relates to improvements in spacing apparatus and is particularly adapted for use on bread slicing machines.

The objects of my invention are to provide means by which the spacing of a plurality of uniformly spaced blocks or units, mounted upon a shaft or other support, may be changed uniformly without changing their angular position upon the shaft or support; to provide improved means by which a plurality of supports for the slicing blades of a bread slicing machine of the reciprocating type may be uniformly and simultaneously changed so as to provide for cutting either thinner or thicker slices, within fixed limits; to provide means by which the spacing of one or more uniformly spaced members adapted to guide and space the blades of a slicing machine of the endless band-blade type may be uniformly and simultaneously changed to provide means by which a plurality of co-acting threads of different pitches may be used to uniformly spread and uniformly gather a plurality of members slidably mounted upon a shaft.

I attain these objects by the means illustrated in the accompanying drawings, in which:

Figure 1 is a side elevation of a band-blade slicing machine, with one form of my apparatus mounted thereon;

Figure 2 is a rear elevation of the machine with the same form of spacing apparatus mounted thereon, but with the ends of the guide fingers omitted for clearness;

Figure 3 is an enlarged detail in section on the line 3—3 of Figure 2;

Figure 4 is a detail view of an alternate means for retracting the movable members, employing a compression spring to retract them;

Figure 5 is an enlarged detail of the shaft in section and shows a side view of one of the spacing members or units mounted thereon;

Figure 6 is an enlarged detail plan view of a part of the lower series of spacing members, with slotted fingers secured therein in section on the line 6—6 of Figure 5;

Figure 7 shows side and end views of one of the spacing rings, with pin for securing same to its shaft;

Figure 8 shows edge and side elevations of one of the steel washers or separators;

Figure 9 is a side view of Figure 10, which is an enlarged detail showing my preferred form of retracting means, comprising a block threaded upon the end of the carrying shaft, with a relatively coarse thread so proportioned that the block will travel a distance equal to the sum of the distances traveled by the respective spacing units;

Figure 11 is a side elevation of the block, 39a.

Figures 12 and 13 are enlarged details showing a form of mounting which permits the angle of

the spacing units relative to the plane of the slicing blades, to be varied;

Figure 14 is an enlarged detail of an alternate form of means for retracting the spacing units;

Figures 15, 16 and 17 show my apparatus as applied to supporting units which carry the slicing blades of a reciprocating slicing machine;

Figure 15 shows the side frames of such a machine in section with one of the reciprocating frames partly in section;

Figure 16 shows a top or plan view of a pair of reciprocating frames mounted in the side frame of a slicing machine with the reciprocating frames in section on the line 16—16 of Figure 15;

Figure 17 shows a sectional elevation on the line 17—17 of Figure 15.

While my invention is primarily designed for slicing machines of both the band-blade and reciprocating types, it obviously may be applied to any kind of machinery where a plurality of spacing units arranged in a series, are employed, and the spacing of which must be changed or varied from time to time.

As applied to a bread slicing machine of the band-blade type, my invention comprises a threaded shaft, 16, or a pair of spaced shafts, 16—18, revolvably mounted in the frame of a machine. Hubs, 4 and 5, united to the frame, may be utilized, having bores formed therein in which the shafts are revolvably mounted with projecting ends upon which hand wheels, 15—17, may be secured to rotate the shafts, 16 and 18.

Each shaft has a slot or groove, 30—32, cut therein extending lengthwise of the shaft. A suitable stop, 4a, may be mounted upon the shaft and secured by a pin or other suitable means.

Upon each shaft I mount a plurality of spacing rings, 28, each of which is provided with a central bore, 28', fitting smoothly upon the shaft and enabling it to slide longitudinally thereon freely. Each spacing ring has means, such as a pin 35, united thereto, the inner end of which fits in and is slidable in the groove, 30—32, of the shaft and presents the rotation of the spacing ring relative to the shaft.

The periphery of each spacing ring is threaded with a relatively fine thread, 28'', (preferably of a gauge permitting 24 to 48 threads per lineal inch of the shaft).

Upon the shafts 16—18 respectively I mount a series of supporting members 27—27', each of which has a central bore of a diameter corresponding to the diameter of the spacing rings 28. These bores are provided with internal threads 28''' (Figure 6) which are complementary to the external threads 28'' of the spacing rings 28 and designed to mesh therewith.

The supporting members and spacing rings may be of any desired length or thickness, but I prefer to form them of about the same thickness,

as shown in Figure 8, and of such proportions that when the spacing rings are entirely screwed into their corresponding supporting members, the blade guides will hold the blades about three-eighths of an inch apart and when the rings are unscrewed to the full distance permitted by the stops 4 and 24 and 39a, the guides will hold the blades about half an inch apart. In common practice the most desired thickness for slices of bread have been found to run within these limits.

In assembling each series of guides, each spacing ring is screwed just half way into the bores of one of the supporting members before being placed upon the shafts 16-18 and when so assembled, it is obvious that when the shafts are turned in one direction, the rings 28 will be screwed into the supporting members 21-21' so as to permit each series of supporting members to be contracted.

In order to permit the spacing rings to force the supporting members apart when the shafts 16-18 are turned in the opposite direction, I mount between one end of each spacing ring and the supporting member adjacent thereto, a washer 36, which may be of thin steel or other suitable material. These washers are provided with bores 37 which permit them to slide freely upon the shafts 16-18, but are too small to permit the spacing rings 28 to enter them. Thus the free end of each spacing ring abuts against the washer adjacent thereto while its opposite end is screwed into the next succeeding supporting member.

When proportioned as above described, the threaded portions of the rings in contact with the supporting members, in combination with the washers, will afford a firm support for the supporting members and the guide fingers united thereto.

I use the term "ends" as applied to the spacing rings to designate the flat surfaces thereof. The outermost supporting member of each series may bear against the block 39a or 25 or against the spring 37a, and the innermost supporting member of each series may be held stationary and kept in fixed position by the hubs 4 or 5 or the stops 4a.

In order to prevent rotation of the supporting members, 21-21', upon the shafts carrying them, I prefer to form integral with each supporting member an extension, 21'', which has a bore, 27a, formed therein adapting it to be mounted and to slide freely upon a non-rotatable shaft, 19-19', one end of which may be secured in the hub, 4-4', or the saddle, 39, hereafter described, so as to extend transversely of the machine parallel to the shaft, 18.

The outer end of the shaft, 18, is provided with threads, 18', which are relatively much coarser than the threads of the spacing rings. I prefer a pitch for these threads of about one inch for each inch in diameter of the shaft.

Upon the threaded end, I mount an internally threaded sleeve or block, 39a, which may be formed with an extension, 27'', to embrace and slide upon the shaft, 19', as shown in Figure 10, or which may be a sleeve, 49, provided with a handle, 50, as shown in Figure 14, and manually operable by said handle.

Another form of sleeve is shown in Figure 2 in which the sleeve, 25, is provided with a beveled face which bears against a stop-block, 22', having a beveled flange, 22, united thereto which corresponds to the beveled face, 33, of the sleeve, 25.

The sleeve, 25, is provided with an extension, 27'', corresponding to the extensions of the sup-

porting members and likewise slidably mounted upon the shaft, 19.

Each supporting member, 21-21', has united thereto a slotted member, 31', adapted to contact the blades by means of a slot, 14'-14'', formed therein, and to space the blades of each series to correspond with the spacing of the supporting members.

In Figures 1, 5, etc., I have shown such guiding members in the form of slotted fingers, but it is obvious that any desired form of guide may be united thereto or the supporting members themselves may be sufficiently enlarged to contact the blades and may be slotted to receive them.

When my invention is applied to a bread slicing machine of the reciprocating type, an additional shaft may be utilized as heretofore described to keep the spacing members in a fixed angular position with reference to the shaft upon which the spacing rings are mounted, but in order to reduce weight, I prefer to keep the supporting members from rotation by forming the upper and lower cross-members of each reciprocating frame in the form of a sleeve, 51, in which the shafts, 54, may be mounted upon suitable bearings, 54b, and having a longitudinal opening, 60, extending lengthwise thereof through which extensions, 51a, of the supporting members, 51, may extend,

The extensions, 51a, and the edges of the opening, 60, bearing against them, perform the same function as the extensions, 21'', and the shaft, 19', in Figure 1.

In reciprocating machines, instead of having slotted fingers mounted upon the supporting members, the extensions, 51a, are themselves slotted and those slots straddle and embrace the ends of the slicing blades, 61, which may be secured therein by pins, 62. In such cases, the spacing of the pin holes in the blades is made small enough so that driving the pins into place, will cause tension upon the blades and tighten them sufficiently without the use of springs, but it is obvious that, if desired, any of the spring or other resilient fastening means in common use may be employed.

As an alternative fastening and in order to permit angular adjustment of the spacing members relative to the cutting plane of the blades, I mount a saddle, 39, upon the hub, 5, and mount one end of the shaft, 19', in the saddle, 39, instead of in the hub, 5.

The saddle, 39, is provided with a slot, 40, through which cap screws, 41-41', extend into the hub to secure the saddle to the hub. By loosening these cap screws, the saddle may be turned into any desired angular position around the hub within its limits and then fixed in such position by tightening the cap screws.

Feed and discharge tables, 43 and 45, supported by arms 42 and 46, may be mounted upon an extension, 44, united to the saddle and in that way the angle of the feed and discharge tables may be varied to correspond with the angle of the fingers, 31'. The upper hub, 4, may be provided with a similar saddle so that the angular position of the upper supporting members may be similarly varied.

It will be noted that with the forms shown in Figures 2 and 11, the end sleeves or blocks, 25 and 39a, travel along the shaft whenever it is rotated by the hand-wheel, 15, a distance equal to the sum of the distances of the travel of all of the spacing members upon that particular shaft and that this movement is automatic in both directions, while with the form of sleeve 75

or nut shown in Figure 14, the sleeve, 49, must be turned away from the spacing members before the shaft, 18, can be rotated and after being so turned away, the shaft may be rotated so as to drive the spacing members apart uniformly by tightening the sleeve, 49, upon the threads, 18', of the shaft, 18, and the spacing members may be retracted or forced together so as to take up any slack there may be between them and this operation must be manually performed.

Another form for automatically retracting the spacing members is shown in Figure 4 and consists of a spring, 31a, mounted upon the end of the shaft, 18, one end of which bears against a pin, 38, and the other end of which bears against and exerts pressure upon the adjacent spacing member, 21'. This spring must be of sufficient strength and length to cause the spacing members to travel the necessary distance to take up any slack that might be left between the spacing members when the shaft is so turned as to cause the spacing rings to be turned so as to re-enter, more or less, the supporting members.

In order to synchronize the spacing of the spacing members upon both the upper and lower shafts, any of the means of so doing in common use for similar purposes may be utilized, one form of which is shown in my co-pending application dated October 25, 1937, filed October 30, 1937, Serial No. 171,866.

A convenient form for this apparatus is shown in Figures 15, 16 and 17 wherein a worm gear, 55a, is mounted upon the corresponding end of each of the upper and lower shafts, 54, and a vertical shaft, 55, is mounted in the frame carrying at each end thereof worms, 54a, which mesh with the worm gears, 55a, upon the shafts, 54.

A hand-wheel, 56, and the shaft, 55, will turn the worms, 54a, and cause them to turn the worm gears, 55a. The shaft, 55, being at one side of the frame, will clear the loaves of bread being sliced and may be permanently mounted in the upper and lower frame members, 51.

The frame members, 51, may be provided with the usual V-shaped guides, 52, mounted to travel vertically in V-shaped grooves formed in the side frames, 50, of the slicing machine.

The reciprocating frames comprising upper and lower sleeves, 51, and side members, 53, are preferably cast integral, but may be built up or assembled in any desired way.

In the operation of my invention, the apparatus embodying it is first assembled by inserting the pins, 35, in the respective spacing rings, 28, and then screwing the spacing rings, 28, into their corresponding spacing members, 21, until the edges coincide. The spacing members, 21, with the spacing rings inside of them are then slid upon the shaft, 18, with the pins, 35, projecting into the groove, 32, and at the same time the extensions, 21'', are slid onto the corresponding shaft, 19'.

Between successive spacing members, the flat steel washers, 36, are inserted and slid upon the shaft, 18.

The sleeve, 39a, is likewise mounted upon the shaft, 18, and screwed down to its desired position, and the extension, 21'', is then slid upon the end of the shaft, 19'.

The shafts, 18 and 19', are then inserted in the corresponding bores in the hub, 4, and the hand-wheel, 17, is secured upon the end of the shaft, 18, and the shaft, 19', secured in place by a pin.

If the saddle, 38, is utilized, the shaft, 18, is

secured in the hub, 5, and the shaft, 19', secured in a suitable opening formed in the saddle.

The cutting blades, 14, are then mounted upon the pulleys, 8 and 9, in crossed or figure 8 form and the blades inserted in the slots of the finger, 31 and 31'. The blades are then tightened by the eccentric, 12, and the machine is then ready to start.

The spaced pulleys, eccentric adjustment and driving means for band-blade machines are in common use and well known and I make no claim to those parts of the machine in this application.

When my apparatus is applied to a reciprocating machine, bearings, 54b, are mounted upon the ends of the shaft, 54, in order to position them within the sleeves, 51, and the spacing units, with the intervening steel washers, are mounted upon the shafts, 54, together with the sleeves, 39a, or other retracting devices, as desired, are mounted upon the shafts between the bearings, 54b, similarly to the method above described, but with this difference, that as the spacing members, 51, in a reciprocating machine must be spaced to carry alternate blades, the spacing rings, 59, must be longer than the spacing rings, 28.

In the reciprocating machine, instead of spacing members carrying slotted fingers to guide the blades, they carry slotted fingers or extensions, 57a, in which the blades, 61, are fastened by pins, 62, and instead of the hand-wheel, 56, being attached directly to the end of the shaft, 54, it is, preferable to mount it upon a shaft carrying a work, 54a, because the tension of the blades upon the bearing members, 57, will cause so much friction that greater power is required to turn the shaft, 54, and the spacing rings, 59.

It is obvious that various modifications of the apparatus shown may be made without departing from the spirit of my invention and I do not limit my claims to the precise forms shown and described herein.

I claim:

1. A mechanical movement for spacing apparatus comprising a rotatable shaft, a series of externally threaded spacing rings keyed to but slidable on such shaft, a corresponding series of non-rotatable internally threaded supporting members having the internal threads of each respective supporting member arranged to mesh in whole or in part with the external threads of its corresponding spacing ring to form pairs, each pair comprising one spacing ring and the supporting member threaded thereon, and a series of washers each having an external diameter greater than the external diameter of the adjacent threaded spacing rings slidably mounted upon such shaft interposed between and separating said pairs from each other.

2. A mechanical movement for spacing apparatus as set out in claim 1, said spacing rings being arranged to exert substantially uniform pressure in one direction upon the supporting members into which they are respectively threaded and to exert pressure in the opposite direction against the washers adjacent thereto respectively when the shaft is turned in one direction, and to release or reduce such pressure as and when the shaft is turned in the opposite direction.

3. A structure as defined in claim 1, and means comprising a stop united to the shaft at one end thereof and a non-rotatable block threaded upon the shaft at the other end thereof and threaded upon the shaft with threads having a pitch equal to the sum of the pitches of all the spacing rings.

4. A structure as defined in claim 1, and means comprising a stop united to the shaft at one end thereof and a non-rotatable block threaded upon the shaft at the other end thereof and threaded upon the shaft with threads having a pitch equal to the sum of the pitches of all the spacing rings to permit spreading of the succeeding supporting members when the shaft is turned in one direction and to retract said spacing members uniformly when the shaft is turned in the opposite direction.

5. A mechanical movement comprising a structure as defined in claim 1, in combination with means for rotating the shaft in either direction.

10. In a bread slicing machine, the combination with a supporting frame having a series of slicing blades movably mounted thereon, of a rotatable shaft mounted upon the frame and extending transversely of the machine parallel to the cutting plane or planes of the blades, a groove formed in said shaft extending longitudinally thereof, a plurality of spacing rings slidably mounted upon said shafts, means comprising pins or keys united to the spacing rings and extending into said groove to cause said rings to rotate with said shaft, external threads formed upon the peripheries of the spacing rings, a corresponding plurality of annular internally threaded guiding and supporting members separately mounted upon said spacing rings respectively, with threads in mesh with the threads of said rings and in paired relation, each ring and supporting member thereon constituting a pair, spacing washers having a central bore corresponding in diameter with the shaft and having an external diameter larger than the spacing rings slidably mounted upon said shaft in alternation with the aforesaid pairs, means to secure the supporting members against rotation, and means to manually rotate the shaft in either direction.

15. A mechanical movement comprising a structure as defined in claim 1, in combination with means slidably mounted upon the shaft to contract the spacing of the spacing members, washers and spacing rings when the shaft is turned in a direction which causes the spacing rings to enter farther into the supporting members with which they are in mesh respectively.

20. 7. A mechanical movement for blade-spacing apparatus comprising a rotatable shaft having mounted thereon a plurality of spacing rings keyed to but slidable on such shaft and having external threads, a corresponding plurality of non-rotatable internally threaded supporting members mounted upon the spacing rings respectively upon the threads in mesh, and a plurality of washers each having an external diameter greater than the external diameter of the adjacent threaded spacing rings slidably mounted upon such shaft and interposed respectively between the rings carrying the supporting members, the parts upon the shaft being arranged in series in the following order throughout the series, to-wit: a supporting member, a spacing ring, a washer, and the bore of the washers being smaller 30 in diameter than the outer diameter of the adjacent spacing rings.

25. 8. A mechanical movement for blade-spacing apparatus comprising a rotatable shaft, a plurality of externally threaded spacing rings keyed to and slidable upon said shaft, a corresponding plurality of annular blade-supporting members mounted upon said spacing rings and having internal threads in mesh with the external threads of the spacing rings for at least a part of the length of said blade-supporting members, a corresponding plurality of washers slidably mounted upon the shaft each washer having a bore smaller in diameter than the outer diameter of the spacing rings and acting to separate one end of each spacing ring from the next succeeding blade-supporting member, and means to secure the blade-supporting members against rotation.

35. 9. A mechanical movement for blade-spacing apparatus comprising a rotatable shaft, a plurality of externally threaded spacing rings keyed to and slidable upon said shaft, a corresponding plurality of annular blade-supporting members mounted upon said spacing rings and having internal threads in mesh with the external threads of the spacing rings for at least a part of the length of said blade-supporting members, a corresponding plurality of washers slidably mounted upon the shaft each washer having an external diameter greater than the external diameter of the adjacent threaded spacing rings, and said washers having bores smaller than the external diameter of the ends of the spacing rings and acting to separate one end only of each spacing ring from the next succeeding blade-supporting member, a crossbar spaced from and parallel to

paired relation, each ring and supporting member thereon constituting a pair and all of the threads of said spacing rings and supporting members having the same pitch and direction, 5 spacing washers having a central bore corresponding in diameter with the shaft and having an external diameter larger than the spacing rings slidably mounted upon said shaft in alternation with the aforesaid pairs, means to secure 10 the supporting members against rotation, and a manually operable handwheel united to the shaft at one end to rotate the shaft in either direction.

13. In a bread slicing machine, the combination 15 with a structure as set out in claim 12, and a stop united to the opposite end of the shaft to limit the travel of the series of pairs in that direction.

14. A bread slicing machine comprising a supporting frame having a series of slicing blades 20 movably mounted thereon, of a rotatable shaft mounted upon the frame and extending transversely of the machine parallel to the cutting plane or planes of the blades, a groove formed in said shaft extending longitudinally thereof, a 25 plurality of spacing rings slidably mounted upon said shafts, pins or keys united to the spacing rings and extending into said groove to cause said rings to rotate with said shaft, external threads formed upon the peripheries of the spacing rings, 30 a corresponding plurality of annular internally threaded non-rotatable supporting members separately mounted upon said spacing rings respectively, with threads in mesh with the threads of said rings and in paired relation, each ring and 35 supporting member thereon constituting a pair, spacing washers having a central bore corresponding in diameter with the shaft and having an external diameter larger than the spacing rings slidably mounted upon said shaft in alternation 40 with the aforesaid pairs, and slotted fingers united to the supporting members respectively to straddle and space the slicing blades.

15. A bread slicing machine comprising a supporting frame having a series of slicing blades 45 movably mounted thereon, of a rotatable shaft mounted upon the frame and extending transversely of the machine parallel to the cutting plane or planes of the blades, a groove formed in said shaft extending longitudinally thereof, a 50 plurality of spacing rings slidably mounted upon said shafts, pins or keys united to the spacing rings and extending into said groove to cause said rings to rotate with said shaft, external threads formed upon the peripheries of the spacing rings, a corresponding plurality of annular internally threaded 55 non-rotatable supporting members separately mounted upon said spacing rings respectively, with threads in mesh with the threads of said rings and in paired relation, each ring and supporting member thereon constituting a pair, spacing washers having a central bore corresponding in diameter with the shaft and having an external diameter larger than the spacing rings slidably mounted upon said shaft in alternation 60 with the aforesaid pairs, and fingers united to the supporting members respectively and also united to one end of the slicing blades respectively.

16. A bread slicing machine as described in 65 claim 14, an extension formed integral with each of the supporting members and having a bore formed therein, and an auxiliary shaft mounted upon the frame parallel to said rotatable shaft and extending through the bores of the aforesaid

extensions to secure the supporting members against rotation with the rotatable shaft.

17. A bread slicing machine as described in 70 claim 14, an extension formed integral with each of the supporting members and having a bore formed therein, an auxiliary shaft mounted upon the frame parallel to said rotatable shaft and extending through the bores of the aforesaid extensions to secure the supporting members against rotation with the rotatable shaft, a handwheel 10 united to the rotatable shaft to rotate same in either direction, and a compression spring mounted upon the outer end of the rotatable shaft to exert continuous pressure upon the outermost supporting member.

18. A bread slicing machine as defined in claim 14, an extension formed integral with each of the supporting members and having a bore formed therein, an auxiliary shaft mounted upon the frame parallel to said rotatable shaft and extending through the bores of the aforesaid extensions to secure the supporting members against rotation with the rotatable shaft, a handwheel 20 united to the rotatable shaft to rotate same in either direction, and a sleeve threaded upon the opposite end of said shaft to engage the outermost supporting member.

19. A bread slicing machine as defined in claim 14, and a corresponding rotatable shaft mounted upon the frame spaced apart from the first shaft 30 and having similar series of spacing rings, washers, non-rotatable supporting members and fingers mounted thereon, the slicing blades being pivotally united to the fingers of one series of supporting members and being united by a resilient 35 connection to the fingers of the other series of supporting members.

20. In a bread slicing machine comprising a supporting frame having a series of slicing blades 40 movably mounted thereon, of a rotatable shaft mounted upon the frame and extending transversely of the machine parallel to the cutting plane or planes of the blades, a groove formed in said shaft extending longitudinally thereof, a 45 plurality of spacing rings slidably mounted upon said shafts, pins or keys united to the spacing rings and extending into said groove to cause said rings to rotate with said shaft, external threads formed upon the peripheries of the spacing rings, a corresponding plurality of annular internally threaded 50 non-rotatable supporting members separately mounted upon said spacing rings respectively, with threads in mesh with the threads of said rings and in paired relation, each ring and supporting member thereon constituting a pair, spacing washers having a central bore corresponding in diameter with the shaft and having an external diameter larger than the spacing rings slidably mounted upon said shaft in alternation 55 with the aforesaid pairs, a corresponding rotatable shaft mounted upon the frame spaced apart from the first shaft and having similar series of spacing rings, washers, non-rotatable supporting members and fingers mounted thereon, the slicing blades being rigidly united to the fingers of one series of supporting members and being united by a resilient connection to the fingers of the other series of supporting members.

21. In a bread slicing machine comprising a supporting frame having a series of slicing blades 60 movably mounted thereon, of a rotatable shaft mounted upon the frame and extending transversely of the machine parallel to the cutting plane or planes of the blades, a groove formed in said shaft extending longitudinally thereof, a plurality of spacing rings slidably mounted upon said shafts, pins or keys united to the spacing rings and extending into said groove to cause said rings to rotate with said shaft, external threads formed upon the peripheries of the spacing rings, a corresponding plurality of annular internally threaded non-rotatable supporting members separately mounted upon said spacing rings respectively, with threads in mesh with the threads of said rings and in paired relation, each ring and supporting member thereon constituting a pair, spacing washers having a central bore corresponding in diameter with the shaft and having an external diameter larger than the spacing rings slidably mounted upon said shaft in alternation with the aforesaid pairs, a corresponding rotatable shaft mounted upon the frame spaced apart from the first shaft and having similar series of spacing rings, washers, non-rotatable supporting members and fingers mounted thereon, the slicing blades being rigidly united to the fingers of one series of supporting members and being united by a resilient connection to the fingers of the other series of supporting members, stops 65 united to the shafts respectively at one end, and manually operable handwheels mounted upon the other ends of the shafts respectively to rotate same in either direction.

HARRY J. CRINER.
